UNITED STATES PATENT OFFICE.

REZIN B. BENFORD, OF PITTSBURG, PENNSYLVANIA, ASSIGNOR OF ONE-THIRD TO JOHN T. MATTHEWS AND ONE-THIRD TO CHARLES W. WALLACE, OF PITTSBURG, PENNSYLVANIA.

CROSS-LINE BUCKLE.

No. 830,489.

Specification of Letters Patent.

Patented Sept. 11, 1906.

Application filed December 22, 1905. Serial No. 292,994.

To all whom it may concern:

Be it known that I, REZIN B. BENFORD, a citizen of the United States, residing at Pittsburg, in the county of Allegheny and State 5 of Pennsylvania, have invented certain new and useful Improvements in Cross-Line Buckles, of which the following is a specification.

The object of this invention is to provide a 10 novel form of cross-line buckle embodying a construction which may be cheaply manufactured and which facilitates the attachment, detachment, and adjustment of the strap parts connected therewith in the practical use thereof.

For a full description of the invention and the merits thereof and also to acquire a knowledge of the details of construction of the means for effecting the result reference 20 is to be had to the following description and accompanying drawings, in which—

Figure 1 is a perspective view of a cross-line buckle, showing the strap parts applied thereto. Fig. 2 is a perspective view showing 25 the buckle alone. Fig. 3 is a cross-section taken on the line X X of Fig. 4. Fig. 4 is a top plan view of the buckle.

Corresponding and like parts are referred to in the following description and indicated 30 in all the views of the drawings by the same reference characters.

Referring to the drawings, the long line is indicated at 1 and the short line at 2. The buckle is preferably made of wire of suitable 35 gage to lend the necessary strength and rigidity thereto, this construction reducing the cost of manufacture and simplifying the form of the buckle in an evident manner.

Specifically describing the invention, the 40 buckle comprises a main frame 3 of approximately rectangular form, an auxiliary frame-piece 4, projecting from one side of the main frame 3 and connected with the latter at a point intermediate the ends of its sides. The 45 frame-piece 4 is of approximately U form, and the sides of the same are attached to the sides of the frame 3 by means of a main cross-bar 5. The cross-bar 5 is connected at its ends with the sides of the frame 3 and is 50 formed with loops or eyes 6, receiving not only the sides of the frame 3, but also the terminals of the sides of the frame-piece 4. The terminals of the sides of the frame-piece

4 are formed with grooved portions 7, which are engaged by the loops or eyes 6.

In order to prevent the cross-bar 5 from slipping along the sides of the frame 3, it is designed to form grooves in the frame sides as well, so that the part 5 is interlocked virtually with both the frame 3 and the frame-piece 4. The frame-piece 4 has the sides thereof curved, so that said frame-piece will extend outwardly from the frame 3 of the buckle at its outer end, the above admitting of free play of the strap parts when properly attached to the buckle. The frame of the cross-bar 5 is made from wire, the ends of which are turned to form the loops or eyes 6, and said cross-bar is formed with an intermediate loop 8, which admits of pivotal connection of a downwardly-swinging tongue 9 with the cross-bar. The tongue 9 is formed with a loop at one end, passing through the loop 8, and said tongue is adapted for pivotal movement toward and from one side of 75 the frame 3. The frame-piece 4 is also provided with a cross-bar 10, which cross-bar is constructed similar to the cross-bar 5, being provided with loops 11 at its ends, which receive the sides of the frame-piece 4, firmly 80 attaching the cross-bar 10 thereto. While the intermediate loop 8 of the cross-bar 5 is arranged at approximately a right angle to the frame 1, a similar loop 12, intermediate of the ends of the cross-bar 10, is located approximately in the plane of the frame-piece 4 and forms a means for pivotally connecting a relatively upwardly swinging tongue 13, which is carried by the auxiliary frame-piece 4, before described. The tongues 9 and 13 90 are movable in opposite directions and operate on opposite sides of the frame 3. The tongue 13 is formed with a loop 14 at one of its ends, which passes through the loop 12, affording a mounting similar to the mounting of the tongue 9 on the loop 8. A keeper 95 is applied to the frame 3 near one end thereof and consists of a transverse bar 15, having downwardly-extending end portions 16, formed with eyes 17, receiving the sides of 100 the frame 3. The keeper 15 is designed to retain an end of the short line 2 in place with regard to the buckle and prevent the same from movement.

The arrangement of the strap parts 1 and 2 105 is obvious, and the manner of attaching, de-

taching, and adjusting the same need not be specifically described. It will be understood that all of the parts hereinbefore set forth with respect to the buckle structure are 5 made of wire which is bent into suitable form.

Having thus described the invention, what is claimed as new is—

1. A cross-line buckle comprising a main frame of approximately rectangular form, an auxiliary frame-piece of approximately U form attached to the main frame, said frame-piece having its sides connected with the sides of the frame at a point between the ends 15 of the latter, a main cross-bar for the frame having its ends bent to form loops receiving the sides of the frame and the terminal portions of the sides of the frame-piece, said frame-piece curving away from the frame toward its outer end, a cross-bar applied to the auxiliary frame-piece, the main cross-bar being formed with an intermediate loop, a tongue formed with a loop received by the loop of said cross-bar and adapted for swinging movement toward and from one side of 40 the frame, a cross-bar applied to the auxiliary frame-piece and having its ends bent to form loops receiving the sides of the frame-piece and also formed with an intermediate loop, a second tongue having pivotal connection with the loop of the cross-bar of the auxiliary frame-piece, and a keeper applied to one end of the frame and comprising a transverse bar having its ends projecting downwardly and formed with eyes receiving the 50 sides of said frame.
2. A cross-line buckle comprising a main frame of approximately rectangular form, an auxiliary frame-piece of approximately U form attached to the main frame, said frame-piece having its sides connected with the sides of the frame at a point between the ends 25

of the latter, a main cross-bar for the frame 30 having its ends bent to form loops receiving the sides of the frame and the terminal portions of the sides of the frame-piece, said frame-piece curving away from the frame toward its outer end, a cross-bar applied to the 35 auxiliary frame-piece, the main cross-bar being formed with an intermediate loop, a tongue formed with a loop received by the loop of said cross-bar and adapted for swinging movement toward and from one side of 40 the frame, a cross-bar applied to the auxiliary frame-piece and having its ends bent to form loops receiving the sides of the frame-piece and also formed with an intermediate loop, a second tongue having pivotal connection with the loop of the cross-bar of the auxiliary frame-piece, and a keeper applied to one end of the frame and comprising a transverse bar having its ends projecting downwardly and formed with eyes receiving the 50 sides of said frame.

In testimony whereof I affix my signature in presence of two witnesses.

REZIN B. BENFORD. [L. s.]
